ATTORNEYS

UNITED STATES PATENT OFFICE.

OCTAVIUS JEFFRIES MORRIS, OF NEW ORLEANS, LOUISIANA, ASSIGNOR OF ONE-HALF
TO FRANK C. BARKS, OF NEW ORLEANS, LOUISIANA.

ICE-MAKING APPARATUS.

Application filed March 10, 1921. Serial No. 451,133.

To all whom it may concern:

Be it known that I, OCTAVIUS J. MORRIS, a citizen of the United States, and a resident of New Orleans, in the parish of Orleans and State of Louisiana, have invented certain new and useful Improvements in Ice-Making Apparatus, of which the following is a specification.

This invention relates to an ice making apparatus, and more particularly to the stationary ice mold type in which the cakes of ice must be lifted directly from the molds.

An object of this invention is to provide improved means for filling the ice molds by overflowing connections from one mold to another.

Another object of this invention is to provide an improved method of purifying the water, during the process of freezing, by overflowing the impurities through the overflow connections.

Another object of this invention is to provide improved means for lifting the cakes of ice from the molds.

It is also an object of the invention to provide improved means for agitating the water in the molds during the process of freezing.

Other objects relating to details of construction, combination and arrangement of parts will later appear in the description to follow.

The invention is illustrated by way of example in the accompanying drawings, in which:

Figure 1 is a vertical longitudinal section taken substantially on the lines 2—2 of Figure 1,

Figure 2 is a vertical transverse section taken substantially on the lines 3—3 of Figure 1,

Figure 3 is an enlarged detail view of the combined ice cake lifting and air introducing element provided for each mold.

Referring to the drawings more particularly A indicates a steel tank in which the freezing process is carried out. The tank may be of any shape or length desired.

In the bottom of the tank there is provided a floor 10 preferably of wood, as shown and upon this floor there is spaced in equal intervals, the cross beams 12 which are also preferably of wood. Each beam has its upper edge protected by a thin sheet metal strip 13. The purpose of the cross

beam 12 is to hold the bottoms of the molds B in spaced relation with one another.

Each mold conforms to the usual shape of an ordinary cake of ice. The molds are placed in rows both longitudinal and transverse of the tank A. A channel or U-shaped beam 15 is secured to each side wall adjacent the top thereof, and extending the entire length of the tank; also a channel beam 16 is secured lengthwise of the tank at the point where the adjacent ends of molds B meet. The molds B are riveted at each of their ends to these channel beams and thus held stationary within the tank A. The channel beams properly space the molds B from the sides of the tank and also from each other, so that a proper circulation of a cooling medium can be made about the molds.

An induction pipe 17 is introduced into the tank A near the top thereof for each longitudinally arranged row of molds B. Each pipe 17 is suitably connected through a regulating valve 18 to a water supply pipe 19; also each longitudinally arranged row of the molds B are provided with an eduction pipe 20 which is suitably connected to a drain pipe 21. Only one eduction and one induction pipe are shown by the drawings in Figure 1, however, the water supply pipe 19 and the drain pipe 21 are disposed in parallel relation with the sides of the tank and hence any number of extensions therefrom could be made.

In the bottom or floor 11 of the tank there is provided a transverse slot or recess 22 in each of which there is positioned a pipe 23. These pipes may be connected in common to a source of steam supply, and serve the purpose of introducing a heating medium about the lower ends of each of the molds B when it is desired to slightly thaw the ice about the interior surface of the molds previous to lifting the same from the molds. For the purpose of introducing air into each of the molds while the water or liquid therein is being frozen, I provide a pair of pipes or supporting members 24, the inner ends of which are connected with the T-shaped member 25, as shown, and their outer ends closed as at 26. Each pipe 24 is also provided with a nipple 27 which is threaded into the sides of the pipe and extending at right angles thereto. Into the vertical stem of the T-fitting 25 there extends a pipe

28 which extends substantially to the bottom of the mold, and has its lower end closed as at 29, said end being provided with perforations through which air may percolate into the surrounding water. The pipe 28 of course communicates from the T-connection 25 with each of the pipes 26. A nipple 27 adjacent one end of the tank is connected to a flexible hose 30 or the like and a valve 31, said valve 31 being in turn connected with a supply of compressed air; also each of the nipples 27 of adjacent molds are connected by means of a hose 32 or other suitable flexible connection. The pipe 26 which is adjacent the opposite end of the tank A need not be provided with a nipple 27.

The description just given includes the means by which the air is circulated upwardly through the water contained in the different molds. The device in each mold including the pipes 24 and 26, and the T-connection 25, may also serve for the purpose of lifting a cake of ice from its mold. A suitable ring 33 is formed on each of the T-connections 25 for this purpose.

It also may be here stated that suitable cross members of wood as shown at 34 are positioned between the adjacent sides of the molds in order to hold the same firmly apart, and also to form additional supporting means for the ends of the pipes 24.

In the operation of the present apparatus the parts are assembled as shown in the drawings and the water turned on from the water supply through the valve 18. The mold into which the water flowing from the pipe 17 empties will of course be first filled and then the water will pass through the pipe or open trough 22 to the adjacent mold, and in this way the molds arranged in this particular longitudinal row will be successively filled. The different ice molds can in this way be filled to the same level and any overflow therefrom may be drained away by the pipe 21. After the molds are filled the valve 18 may be closed, and the valve 31 for introducing the compressed air opened. Through the flexible connections 32 the air is introduced simultaneously into each of the molds B. The air being released at the bottoms of the molds rises swiftly through the water to the top, causing violent agitation in the mold and any impurities in the water are thus expelled to the top and carried out through the drain pipe 21.

This operation is continuous until the ice is formed solidly in each of the molds, at which time the air valve 31 may be closed. It is of course to be understood that the

freezing of the water takes place, due to a cooling liquid being introduced about the different molds.

When it is desired to lift the cakes of ice from the mold, a heating or warming fluid may be substituted for the freezing fluid or medium for a short interval. Also steam may be introduced into the pipes 23 for a short interval. This will slightly melt the ice adjacent the inside surface of the molds, and permit the same to be lifted. A suitable hook or chain may be then inserted in the rings 33 and the ice cakes lifted from their molds. Any suitable means could be employed for removing the pipe 28, and its associated parts from the ice cake after the same has been lifted from its mold.

I claim:

1. A combined air introducing and ice cake lifting means for a mold, comprising in combination a T-fitting, a pipe extending from each horizontal portion thereof, their ends being adapted to rest upon the edges of a mold, a pipe extending from the vertical portion of the T-fitting to approximately the lower end of the mold and communicating with each of the pipes extending from the horizontal portions of the T-fitting, a nipple threaded into each of the pipes extending from the horizontal portions of the T-fitting, and a closure for the outer ends of each of said pipes.

2. A combined air introducing and ice cake lifting means for a mold, comprising in combination a T-fitting, a pipe extending from each horizontal portion thereof, their ends being adapted to rest upon the edges of a mold, a pipe extending from the vertical portion of the T-fitting to approximately the lower end of the mold, and communicating with each of the pipes extending from the horizontal portions of the T-fitting, a nipple threaded into each of the pipes extending from the horizontal portions of the T-fitting, and a closure for the outer ends of each of said pipes, and a ring formed upon the top surface of the T-fitting.

3. A combined air introducing and ice cake lifting means for molds, comprising a tubular cross, the horizontal portion being formed with a rigid eye, and a nipple adjacent each end of the same communicating with the vertical portion thereof.

4. An air introducing means for an ice mold comprising a tubular cross, the horizontal portion communicating with the vertical portion and the horizontal portion having adjacent each of its ends a nipple, said nipple in each instance communicating with the interior thereof.

OCTAVIUS JEFFRIES MORRIS.
